UNITED STATES PATENT OFFICE.

NILS H. ANDERSON, OF MIDDLETOWN, CONNECTICUT, ASSIGNEE, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,219,213.

Specification of Letters Patent. Patented Mar. 13, 1917.

Application filed September 12, 1913. Serial No. 789,418.

To all whom it may concern:

Be it known that I, NILS H. ANDERSON, a citizen of the United States, residing at Middletown, in the county of Middlesex and State of Connecticut, have invented certain new and useful Improvements in Type-Writing Machines, of which the following is a full, clear, and exact description, such as will enable others skilled in the art to which it appertains to make and use the same.

This invention relates to typewriting machines, and with regard to certain more specific features thereof, to the escapement mechanism and intervening parts for controlling the letter-space movement of the carriage.

One of the objects of the present invention is to provide an escapement mechanism which will be efficient in use and silent in operation. A further object is to provide a simple and practical escapement mechanism having few parts which will be cheap to manufacture and assemble. A further object is to provide a mechanism of the first 25 above-mentioned character which will permit a rapid operation of the machine and an accurate, even movement of the carriage, properly timed with relation to the printing moment. Other objects will be in part obvious and in part pointed out hereinafter.

The invention accordingly consists in the features of construction, combinations of elements and arrangement of parts which will be exemplified in the construction herein- 35 after set forth, and the scope of the application of which will be indicated in the following claims.

In the accompanying drawings, in which is illustrated one of the various possible embodiments of the several features of the invention,

Figure 1 is a side elevational view of a portion of a typewriting machine with certain parts in section or broken away for the sake of clearness;

Figs. 2 and 3 are, respectively, an inverted plan and sectional elevation of the escapement mechanism in normal position;

Figs. 4 and 5 are similar views, respectively, of the mechanism in actuated position;

Fig. 6 is an inverted rear elevation of the parts shown in Fig. 2;

Fig. 7 is a sectional elevation of the intervening mechanism between the escapement 55 dogs and the carriage;

Fig. 8 is a sectional plan view of this device showing the tabulator brake;

Fig. 9 is an elevational view taken at right angles to Fig. 7; and

Fig. 10 is a bottom plan detail view.

Similar reference characters refer to similar parts throughout the different views of the drawings.

The escapement mechanism, carriage, and intervening parts hereinafter described will be described with relation to their application to a noiseless typewriter machine, although it is, of course, to be understood that the mechanism may be applied to other forms of typewriting machines as well. The preferred manner in which this escapement is used, is that commonly known to those familiar with the art as "speed" or "reverse escapement"; that is, one in which the teeth 75 of the escapement wheel rest normally, that is when the escapement is inactive, on what may be termed the "fixed dog," the carriage being in position without any material preliminary movement for receiving the impression of the next character. The printing operation is performed before the carriage starts from such position, although the escapement may have been released to admit of such movement at the instant of printing, 80 or immediately previous thereto the inertia of the carriage being such and the speed of printing so high that the impression is made on the paper before the carriage has left its position of rest. This form of escapement 85 may also be used as an ordinary or non-reverse escapement in the sense in which the term is ordinarily understood,—that is, an escapement mechanism in which the teeth of the escapement wheel when in normal or in- 90 active position, rest against the movable dog, the movable dog being released and moved forward for engagement with the next succeeding escapement tooth, just previous to the printing moment, the carriage being 95 either brought to rest temporarily on the fixed dog of the escapement at or just subsequent to the printing moment, depending upon the amount of drop between the two dogs and the speed of the printing opera- 100 tion. This explanation is made in order to

60

bring out more clearly the meaning of this term as well as certain features in connection with the present invention.

Referring now to the drawings in detail, and more particularly to Fig. 1, a platen carriage 1 carries a cylindrical platen roller 2 about which the paper is fed in a well-known manner. Type carriers 3 are adapted to be connected to any suitable form of finger-actuated means (not shown), but preferably of that illustrated and described in my co-pending application, filed August 6, 1913, Serial No. 783,331, to move them into coactive relation with the paper carried by the platen as the carriage moves in a letter-spacing direction. The carriage is supported on a shift rail 4 suitably mounted on arms 5 secured to the frame of the machine, whereby a vertical shift movement of the carriage, either above or below its normal printing position, may be obtained. The letter-spacing movement of the carriage is controlled by a rack and pinion mechanism in which the rack 6 is pivotally mounted upon the carriage and the pinion 7 is secured to the upper end of an escapement shaft 8. The lower end of the escapement shaft is provided with a carriage-controlling rack in the form of an escapement wheel 10 with which dogs carried by a rocker member 11 are adapted to coact. The rocker member 11 is actuated or rocked on each actuation of any character key through a universal bar and rock shaft mechanism.

Referring now in detail to the escapement mechanism, and more particularly to the detailed views of Figs. 2, 3, 4, 5 and 6, bearing in mind that Figs. 2 and 4 are bottom plan views, the escapement rocker 11 is of U-shaped sheet metal construction, as shown more clearly in Fig. 6. This rocker is adapted to oscillate in an escapement bracket 12 on pivot screws 13 engaging centers in the body portion of the rocker. The normally downwardly extending arms 14 and 15 at either end of the body portion are for engagement with the driving connections from the space-bar and universal bar mechanisms, respectively. The body portion of the rocker is provided with oppositely disposed fore and aft projections or arms 16 and 17, the former having an offset portion 18 on which is pivotally mounted what will be hereinafter termed a "fixed dog", 20, by means of a screw and nut 21.

The fixed dog engages normally the escapement wheel 10 at one end, as shown, and is held in its normal position by the action of a coiled spring 22 holding a pin or stud 23 of the dog, to which one end of the spring is connected, against a portion 24 of the forwardly projecting arm 18 of the escapement rocker. On the opposite side of this forwardly projecting arm of the escapement rocker body is a movable dog 25

pivotedly mounted on a screw and nut 26. The forward or normal position of this dog, 25, as shown in Fig. 2, is maintained by the action of the coiled spring 22, which, in addition to being connected to the fixed dog, is also connected at its opposite end 27 to the movable dog, as shown, the one spring, therefore, acting to control both dogs.

In order to avoid any misunderstanding, it may be briefly explained that the fixed dog is fixed only in so far as its operation in controlling the letter-space movement of the carriage is directly concerned; that is, during the usual operation of the machine for feeding the carriage in a letter-spacing direction the dog has a relatively fixed position with respect to the rocker member 11 at all times. Its pivotal mounting is for the purpose of permitting it to swing out of the path of travel of the escapement wheel when the carriage is being back spaced, or when released to permit the carriage to run free under the tabulator action.

The mechanism which controls the normal position of the movable dog, as shown in Fig. 2, or the stopping position of the dog whereby the carriage is silently arrested, is shown in Fig. 4. This mechanism comprises a rearwardly extending portion 30 of the movable dog beyond its pivotal connection provided with a slot or separated members for engagement with the opposite sides of two members 31 and 32 mounted one above the other on a screw and nut 33 passing through an adjusting slot 34 in a rearwardly projecting arm 35 on the body portion of the escapement rocker 11. The under member 31 is that which controls the movement of the movable dog both to its active position when engaged by the escapement wheel, and in the act of silently stopping the carriage, as shown in Fig. 4. This member 31 has a body portion in the form of a split ring 36 which operates as a cushion stop to arrest the movement of the movable dog noiselessly.

The member 32 is a safety member acting to prevent breakage of the member 31 under certain conditions of possible incorrect operation. It will be noted that both of these members 31 and 32 are provided with curved or rounded front ends connected with their body portions by relatively narrow necks whereby they are permitted to have a relative oscillating movement with respect to the part 30 of the movable dog. Bearing in mind that the present invention is described in its preferred embodiment as a "reverse escapement", it will be noted that the escapement wheel rests against the fixed dog 20 when the machine is at rest (Fig. 2), the movable dog being in its forward position ready for engagement with the next succeeding tooth of the escapement wheel, it

being stopped in that position by the action of its slotted end 30 engaging with the rounded end of the member 31. Its normal position is just clear of the tooth of the wheel 10 held by the fixed dog 20 so that the carriage will be permitted to have a free letter-space movement before its next tooth contacts therewith. When the escapement is actuated and the fixed dog is disengaged from the escapement wheel, the next succeeding tooth of the wheel engages the movable dog 25 and moves it to the stopping position, as shown in Fig. 4 of the drawings, where it is again brought to rest by the engagement of the slotted end of the movable dog with the rounded end of the member 31. Since member 31 is provided with a split ring portion 36, there is a slight spring or cushioning action as the dog is brought to rest, which causes the silent arresting of the escapement wheel as above mentioned. The continued movement of the escapement rocker in completing its cycle of operation to normal position, Fig. 2, releases the movable dog 25, which passes forward to its normal position, leaving the escapement wheel bearing against the fixed dog 20 ready for the next printing operation.

30 The action of the safety member 32 is to prevent the breakage of the split ring spring member 36 in case the escapement wheel 10 is reversed by the back-spacing mechanism or otherwise, while the movable dog 25 is in engagement with the escapement wheel. The dotted line in Fig. 4 below the end 31 shows the shape of the end of the member 32 and it will be noted that a slight clearance is provided whereby, if the escapement 35 wheel is reversed while the movable dog is in engagement with a tooth thereof, as shown in Fig. 4, the same is locked by the member 32 against movement without permitting a breaking strain to be brought to 40 bear upon the part 36.

With the escapement used in the reversed form, as above described, a clutch intermediate of the dog rocker and the carriage rack 6 to permit a return of the carriage to 45 line-commencement position is unnecessary, for the backward movement of the carriage brings into action the pivotal mounting 21 of the fixed dog.

To control the relation between the working surfaces of the dogs, or to control the drop from one dog to the other, the shouldered pivot screw 33 upon the shouldered portion of which the members 31 and 32 are adapted to turn, is mounted in the slot 34 50 concentric with the pivot 26 of the movable dog. It will thus be seen that the adjustment of the pivot 33 to various positions in this slot, will control the position of the movable dog and the moment of contact between the next succeeding tooth of the es-

capement wheel and the dog, as well as the amount of drop from the movable dog to the fixed dog. In other words, the free and uninterrupted movement of the escapement wheel before it contacts with the movable dog may be positively controlled.

55 In order to use this escapement as an ordinary or non-reversed escapement, it is only necessary to transfer the working parts from one side of the escapement rocker to the other, the movable dog then being located on the upper surface of the body of the rocker and the fixed dog on the lower surface thereof, or the relative position being reversed to that shown in Figs. 2 and 3. When used in this way the movable dog 60 normally engages the escapement wheel when at rest, and it is, therefore, necessary to provide either a clutch between the escapement wheel and carriage, or to provide the movable dog with a pivot end somewhat similar to the construction of the fixed dog, shown in Figs. 2 and 3, so that it may release when the escapement wheel is reversed.

65 The intervening mechanism between the escapement rocker and the carriage is shown in detail in Figs. 7 to 10 inclusive, and the escapement shaft 8 is secured and rotated at its upper end in a ball-bearing trunnion 40 mounted in an escapement shaft bracket 41, which bracket is secured to the fixed carriage shift rail 4 along which the carriage travels. The purpose of the trunnion mounting is to admit of a fore and aft adjusting movement of the carriage when using different thicknesses or varying numbers of sheets of paper in order that the surface of the outer sheet may be properly positioned with respect to the printing plane located at the end of the path of travel of the several type carriers. The upper end of the escapement shaft 8 is reduced in diameter and carries an upper and lower ball raceway 42 and 43, between which are positioned ball bearings 44 running in the trunnion ring 40. The upper raceway has a flange 45 extending partially over the upper surface of the trunnion ring to prevent dust and dirt from clogging the ball bearings. The whole combination is locked in 70 place by lock nut 46 acting upon the upper ball raceway, which is also threaded for engagement with the reduced end of the escapement shaft.

75 The lower end of the shaft is positioned in a plate 47 mounted in the escapement bracket 12 and carries the escapement wheel 10 and tabulator brake disk 48, with which a suitable brake shoe 50 is adapted to coact when the tabulating mechanism (not herein shown or described) is brought into operation. A hub 51 on which the escapement wheel is keyed loosely surrounds the escapement shaft to permit fore and aft movement of its upper end, as when the platen is moved.

relatively to the normal printing plane and also provides a support for a plurality of rollers 52 turning about horizontal axes substantially tangentially disposed with respect to the escapement shaft 8, as shown in Fig. 10. These rolls coact with vertical grooves 53 in the escapement shaft, and the purpose of this construction is to key the hub and shaft and also to admit of the shifting of the carriage with the shift rail 4 to which the upper end of the escapement shaft is connected through the rack and pinion mechanism 6 and 7. This construction does away with a telescopic escapement shaft or a long shift pinion 7 and greatly facilitates the assembling of the parts when constructing the machine, as well as provides a stronger, cheaper and more durable device.

It is believed that the operation of this device is clear from the above description and a reiteration thereof is unnecessary. The invention is simple and practical in construction and is silent and rapid in its operation, thereby accomplishing, among others, all of the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In an escapement mechanism for typewriters, in combination, a feed rack, a dog rocker, a dog carrier medially pivoted on said rocker and extending toward and away from said rack, and a pivotal member carried by said rocker to coact with that portion of said dog carrier on the side of its pivotal axis away from said rack for controlling said dog carrier.

2. In an escapement mechanism for typewriters, in combination, a horizontally disposed dog rocker having front and rear arms, a movable dog carrier mounted upon said front arm, and adjustable means mounted on said rear arm for limiting movement of said dog carrier.

3. In an escapement mechanism, in combination, a rocker member, pivotally mounted dogs mounted upon the opposite sides of said rocker member, one of said dogs having a normally fixed relation and the other of said dogs being movable, and means cooperative with said movable dog adapted to arrest silently the movement of the member to be spaced.

4. In an escapement mechanism, in com-

bination, a rocker member, dogs mounted upon said rocker member, one of said dogs having a normally fixed relation and the other of said dogs being movable, and a plurality of spring means coacting with said movable dog, one of said spring means being in the form of a split ring and adapted to silently arrest the movement of the movable dog when engaged with the member to be spaced.

5. In an escapement mechanism, in combination, a rocker member, a movable dog mounted thereon, and a split ring member coacting with said dog for cushioning its movement.

6. In an escapement mechanism, in combination, a rocker member, a movable dog mounted thereon, a split ring member coacting with said dog for cushioning its movement, and means for adjusting the position of said ring for controlling the position of said dog.

7. In an escapement mechanism, in combination, a rocker member, a dog pivotally mounted intermediate its ends, one end being provided with a tooth adapted to coact with the member to be spaced, and the opposite end being provided with a slot, and a resilient member coacting with the slot for arresting the movement of the dog.

8. In an escapement mechanism, in combination, a rocker member, a dog pivotally mounted intermediate its ends, one end being provided with a tooth adapted to coact with the member to be spaced, and the opposite end being provided with a slot, and a ring member coacting with the slot in the movable dog for silently arresting its movement in one direction.

9. In an escapement mechanism, in combination, a rocker member, a dog pivotally mounted intermediate its ends, one end being provided with a tooth adapted to coact with the member to be spaced, and the opposite end being provided with a slot, and a pivotally mounted split ring member coacting with the movable dog for controlling its position.

10. In an escapement mechanism, in combination, a rocker member, a dog pivotally mounted intermediate its ends, one end being provided with a tooth adapted to coact with the member to be spaced, a ring member coacting with the other end of the movable dog for silently arresting its movement in one direction, and a safety member associated with said ring member.

11. In an escapement mechanism, in combination, a rocker member, a pivotally mounted dog provided with a tooth adapted to coact with the member to be spaced, a ring member coacting with the movable dog for silently arresting its movement in one direction, and a pivotally mounted

- safety member positioned beneath said ring member adapted to coact with the movable dog.
12. In an escapement mechanism, in combination, a rocker member, a fixed dog and movable dog on the opposite side of said rocker member, a spring connected to the tail of said movable dog adapted to hold it in normal forward position, and a second spring adapted to coact with the tail of said dog for cushioning its movement when engaged with the member to be spaced.
14. In an escapement mechanism, in combination, a rocker member, a movable dog on said rocker member pivotally mounted intermediate its ends, a spring connected to the tail of said movable dog adapted to hold it in normal forward position, and a second spring adapted to coact with the tail of said dog for cushioning its movement when engaged with the member to be spaced, said second spring being in the form of a split ring pivotally mounted on one side opposite the point of engagement between the ring and the dog.
14. In an engagement mechanism, in combination, a rocker member, a movable dog on said rocker member pivotally mounted intermediate its ends, a spring connected to the tail of said movable dog adapted to hold it in normal forward position, a second spring adapted to coact with said dog for cushioning its movement when engaged with the member to be spaced, said second spring being in the form of a split ring pivotally mounted on one end opposite the point of engagement between the ring and the dog, and a safety device coacting with said movable dog adapted to prevent excessive strain from being transmitted to the split ring.
15. In an escapement mechanism, in combination, a rocker member having an offset forwardly extending arm, a dog pivotally mounted at the end of said arm, and a second dog pivotally mounted near the middle of said arm but on the opposite side of the rocker member.
16. In an escapement mechanism, in combination, a rocker member having an arm, a dog pivotally mounted at the end of said arm, a second dog mounted near the middle of said arm, a spring connected to the tail of one of said dogs, and a second spring co-acting with the tail of the other of said dogs, said second mentioned spring being adapted to silently arrest the movement of the dog with which it coacts.
17. In an escapement mechanism, in combination, a rocker member, a dog adapted to coact with the member to be spaced, a second dog having a position slightly forward of the tooth of the first dog and out of the plane of the member to be spaced, and
- spring means coacting with said second dog adapted to silently arrest its movement when moved into the plane of and engaged by a subsequent tooth of the member to be spaced, said spring being in the form of a pivotally mounted split ring.
18. In an escapement mechanism, in combination, a rocker member, a holding dog adapted to coact with the member to be spaced, a movable dog having a normal position slightly forward of the tooth of the holding dog and out of the plane of the member to be spaced, spring means coacting with said movable dog adapted to silently arrest its movement when moved into the plane of and engaged by a subsequent tooth of the member to be spaced, and a coiled spring connecting the tails of said dogs, adapted to restore and maintain said parts in normal position.
19. In a typewriting machine, in combination, a shiftable platen carriage, an escapement shaft operatively connected therewith, an escapement wheel mounted on said shaft, and escapement mechanism coacting with said wheel, said escapement shaft and wheel being formed to have a relatively longitudinal movement to permit the carriage to be shifted independently of the escapement mechanism.
20. In a typewriting machine, in combination, a shiftable platen carriage, an escapement shaft having an operative connection therewith, an escapement wheel mounted to rotate with said shaft but permitted to have a longitudinal movement with respect thereto, and a plurality of rollers coacting with said shaft adapted to permit said movement.
21. In an escapement mechanism for typewriters, in combination, a holding dog, a stepping dog, resilient means urging said stepping dog away from said holding dog, and a pivoted member interlocked with said stepping dog to move with and limit movement of the latter.
22. In an escapement mechanism for typewriters, in combination, two eccentrically pivoted members, one an escapement dog and the other a controlling element therefor, said members having coacting parts intermediate their pivotal axes.
23. In an escapement mechanism for typewriters, in combination, a dog, a rocker having a pivoted stepping cog thereon having a recess, and a movable controlling element for said dog having a portion disposed within said recess and coacting with the sides thereof to limit silently the movement of said dog.
24. In an escapement mechanism for typewriters, in combination, a feed rack, a pivoted stepping dog movable in one direction by said rack, spring means for moving said

- dog in the other direction, and a movable member interlocked with said dog for limiting movement of the latter by said rack and by said means.
5. 25. In an escapement mechanism for typewriters, in combination, two eccentrically pivoted members, one an escapement dog and the other a controlling element therefor, said members having coacting parts to limit the pivotal movements of said dog, and means permitting adjustment of the axis of one of said members to vary the arc of movement of said dog.
10. 26. In an escapement mechanism for typewriters, in combination, two eccentrically pivoted members, one an escapement dog and the other a controlling element therefor, said members having interlocked parts to limit the pivotal movements of each, and means permitting adjustment of the axis of said controlling element to vary the arc of movement of said dog.
15. 27. In an escapement mechanism for typewriters, in combination, a rotatable shaft, an escapement rack thereon, and operative connecting means between said elements for insuring synchronous rotative movement while permitting relative axial movement thereof.
20. 28. In an escapement mechanism for typewriters, in combination, a rotatable shaft, an escapement rack thereon, and operative connecting means between said elements including a groove in one and a part on the other fitting said groove for insuring synchronous rotative movement while permitting relative axial movement thereof.
25. 29. In an escapement mechanism for typewriters, in combination, a rotatable shaft, an escapement rack thereon, and operative connecting means between said elements comprising axial grooves in said shaft and rollers carried by said rack working in said grooves for insuring synchronous rotative movement while permitting relative axial movement of said shaft and rack.
30. 30. In an escapement mechanism, in combination, an escapement rack, a dog, a second dog adapted to move toward and away from said first dog, means adapted to provide a continuous yielding resistance to the movement of said second dog in one direction and a yielding stop adapted to limit said movement, and a safety device adapted to coact with said movable dog to avoid undue strain on said yielding stop.
35. 31. In an escapement mechanism, in combination, an escapement rack, a dog, a second dog adapted to move toward and away from said first dog, means adapted to provide a continuous yielding resistance to the movement of said second dog in one direction and a yielding stop adapted to limit said movement, said second dog and said stop comprising a wiper contact connection
- whereby the noise of an impact is avoided, and a safety device adapted to coact with said movable dog to avoid undue strain on said yielding stop.
32. In a typewriting machine, in combination, a shiftable platen carriage, a shift rail along which the carriage is adapted to travel, a bracket carried by said shift rail, a trunnion block carried by the bracket, and an escapement shaft mounted in said trunnion block at one end and carrying an escapement wheel at its opposite end, said escapement wheel being connected to rotate with said shaft and to permit relative longitudinal movement thereof.
33. In a typewriting machine, the combination of a carriage; and escapement mechanism therefor comprising a feed rack, a dog rocker, a stepping dog pivoted on one side of the dog rocker to move in the general direction of movement of the adjacent teeth of the feed rack, and a holding dog pivoted on the other side of the dog rocker for movement thereon at substantially right angles to the direction of movement of the adjacent teeth of the feed rack and into and out of engagement therewith.
34. In a typewriting machine, the combination of a carriage; and escapement mechanism therefor comprising a feed rack, a dog rocker, a stepping dog pivoted on one side of the dog rocker to move in the general direction of movement of the adjacent teeth of the feed rack, a holding dog pivoted on the other side of the dog rocker for movement thereon at substantially right angles to the direction of movement of the adjacent teeth of the feed rack and into and out of engagement therewith, and a single contractile spring operatively connected at one end to the holding dog and at its opposite end to the stepping dog and operative on both dogs.
35. In an escapement for typewriters, in combination, a feed rack, a dog rocker extending substantially in the plane of said rack, a dog carrier pivoted on said rocker and extending substantially at right angles to the direction of movement of the adjacent teeth of said rack, a second dog carrier pivoted on said rocker and extending at an obtuse angle to said first mentioned dog carrier, and spring means urging said carriers to normal position.
36. In an escapement mechanism for typewriters, in combination, a feed rack, a dog rocker extending substantially in the plane of said rack, a dog carrier pivoted on one side of said rocker and extending substantially at right angles to the direction of movement of the adjacent teeth of said rack, a second dog carrier pivoted on the other side of said rocker and extending at an obtuse angle to said first mentioned dog carrier, a stepping dog and a holding dog on

said first and second mentioned dog carriers respectively, and a spring connected to and extending between said dog carriers.

37. In an escapement mechanism for type-writers, in combination, a feed rack, a dog rocker therefor, a dog carrier pivoted on said rocker and extending substantially at right angles to the direction of movement of the adjacent teeth of said rack, a second dog carrier pivoted on said rocker and extending at an obtuse angle to said first mentioned dog carrier, a coil spring connecting

the outer ends of said dog carriers, a fixed stop on said rocker for limiting movement of one of said dog carriers, and a pivoted stop on said rocker for limiting movement of the other of said dog carriers. 15

In testimony whereof I affix my signature, in the presence of two witnesses.

NILS H. ANDERSON.
